UNITED STATES PATENT OFFICE.

DAVID J. SEAMAN, OF SOUTH BEND, INDIANA.

DESIGN FOR FABRIC.

SPECIFICATION forming part of Design No. 34,683, dated June 18, 1901.

Application filed May 24, 1901. Serial No. 61,808. Term of patent 14 years.

To all whom it may concern:

Be it known that I, DAVID J. SEAMAN, a citizen of the United States of America, residing at South Bend, in the county of St. Joseph and State of Indiana, have invented and produced a new and original Design for Fabrics, of which the following is a specification, reference being had to the accompanying drawing, which forms a part hereof.

This design relates to the ornamentation of cotton, silk, woolen, paper, celluloid, and other fabrics.

The leading feature of the design is the representation of double festoons of holly leaves and berries with stars at the ends of the festoons, the alternate stars being supported by wreaths and bows. The festoons A A are

formed of holly leaves and berries, and their ends are caught by wreaths B and bows C. Within the wreaths and on the bows appear stars D, while from the alternate ends or junctions of the festoons depend clusters of holly leaves and berries E and clusters of bells F.

What I claim is—

The design for a fabric herein described and shown.

In testimony whereof I have signed this specification in the presence of two witnesses.

DAVID J. SEAMAN.

Witnesses:

L. CLARENCE BALL,
CHARLES SEAMAN.
